JOHN CHRISTY, OF CLYDE, OHIO.

Letters Patent No. 98,029, dated December 21, 1869.

IMPROVEMENT IN COOPERS' TOOL.

The Schedule referred to in these Letters Patent and making part of the same

To all whom it may concern:

Be it known that I, JOHN CHRISTY, of Clyde, in the county of Sandusky, and State of Ohio, have invented certain new and useful Improvements in Coopers' Tools; and I do hereby declare that the following is a full, clear, and exact description thereof, reference being had to the accompanying drawings, and to the letters of reference marked thereon, which form a part of this specification, in which the figure in the annexed drawing represents a plan view of my coopers' tool.

The nature of my invention consists in constructing a coopers' tool in the manner and for the purpose set forth.

A and B represent the two blades of my invention, and

d e designate the shanks of the same.

The blades A and B are joined together by the pivot *s*. To the end of shaft *e* is pivoted the plate C, the said plate being pivoted at its opposite end to the operating-lever D.

The shank *d* terminates in the holder E, which may be made pointed for the purpose of being driven into

a solid block, when the tool is to be operated, or a receptacle in the block or bench may be made for it.

When the holder is secured in the manner described, the blades are made to perform their office by alternately raising and lowering the handle or operating lever D, which acts on plate C, and plate C acts simultaneously on shank *e* and blade A, and blade A, in conjunction with stationary blade B, performs the cutting-process.

I am aware that there is no novelty in the peculiar construction of the parts which compose this invention, and therefore lay no claim specially to them; but

What I do claim, and desire to secure by Letters Patent, is—

The combination of shanks *d* and *e*, when both are constructed and arranged to operate in the manner described.

In testimony that I claim the foregoing as my own, I affix my signature, in presence of two witnesses.

Witnesses: JOHN CHRISTY.

JOS. ZEPERNICK,
I. JAY NICHOLS.
